Lacy Lacy, Attorney

UNITED STATES PATENT OFFICE.

ADELBERT AUSTIN, OF GREENWOOD, NEW YORK.

CULVERT LINING.

Application filed November 10, 1922. Serial No. 600,105.

To all whom it may concern:

Be it known that I, ADELBERT AUSTIN, a citizen of the United States, residing at Greenwood, in the county of Steuben and State of New York, have invented certain new and useful Improvements in Culvert Linings, of which the following is a specification.

This invention relates to an improved lining for road culverts or the like and seeks, as one of its principal objects, to provide a lining so constructed that, when a culvert becomes choked with sand, mud or gravel, the lining may be removed to clear the culvert, thus dispensing with the necessity for manually digging the clogging substance from the culvert.

A further object of the invention is to provide a lining composed of a plurality of mating units and wherein the units may be drawn from the culvert one by one for carrying the deposits from the culvert.

And the invention has as a still further object to provide a lining wherein the units will be so constructed that in the operation of cleaning a culvert, the material in the units will be retained therein during withdrawal of the units.

Other and incidental objects will appear hereinafter.

In the drawings:

Figure 1 is a vertical sectional view showing my improved lining in conjunction with a conventional road culvert.

Figure 2 is a horizontal sectional view more particularly illustrating the structure of the lining, and

Figure 3 is a detail perspective view showing one of the lining units.

In carrying the invention into effect, I employ a plurality of channel shaped lining units or trays 10. These units may be formed from suitable resilient sheet metal bent to the desired shape and, as clearly brought out in Figures 2 and 3, the units are tapered in width longitudinally thereof so that the upstanding side walls of the units gradually converge toward the rear ends of the units. Riveted or otherwise secured to said side walls at the forward ends of the units are loops 11. In some instances, it may be found desirable to cast the units, in which event the loops 11 may be integrally formed on the side walls of the units, and where the size of the units would render

the units too heavy to be conveniently handled or transported, the units may be split longitudinally into mating sections.

In Figures 1 and 2 of the drawings, I have, for convenience, shown my improved lining in conjunction with a conventional road culvert 12. As will be observed, the units are arranged end to end within the culvert to extend from one end of the culvert to the other and are shaped to conform to the contour of the culvert, it being, of course, understood in this connection, that in any instance where a cylindrical culvert is to be equipped with the lining, the units of the lining will be shaped accordingly. The units are arranged to abut each other so that the flat bottom walls of said units will form a continuous surface at the bottom of the culvert and, as will be noted, the side walls of the units at the smaller ends thereof are disposed to fit between the loops 11 at the larger ends of the units, while the larger ends of the units are of a width to quite snugly fit between the side walls of the culvert. Thus, water may freely flow through the lining and, of course, as sediment is deposited within the culvert, such sediment will be contained within the lining. Accordingly, when the culvert becomes clogged, the lining may be removed for cleaning the culvert. To facilitate this operation, I provide a bail 13 which is formed medially with an eye 14 and equipped at its ends with hooks 15 freely engageable in the loops of the units of the lining. Thus, as suggested in Figure 2, the bail may be engaged with the terminal unit at one end of the culvert, when a draft animal may be hitched to the bail as by a chain or other device, and the unit pulled from the culvert. After the terminal unit has been so withdrawn, the next unit may then be withdrawn and so on until all of the units have been removed. In this connection, attention is directed to the fact that due to the inclination of the side walls of the units, the material in the units will be prevented from discharging therefrom as the units are withdrawn. As will be seen, any rearward slipping of the material in the units during the withdrawal of the units will serve to jam or pack the material between said side walls so that the units cannot be caused to slip forwardly from beneath the material contained therein nor can the ma-

material in the units slide backwardly out of the units. After the units have been displaced, the units may, of course, be readily dumped and cleaned so that the entire operation of cleaning the culvert may be easily and quickly accomplished.

In the foregoing description, I have referred to the invention as a culvert lining and have so illustrated the structure. However, as will be perceived, the invention is also applicable for use in connection with open ditches or other conduits and the term culvert as herein used, is, therefore, intended to cover such adaptations of the invention.

Having thus described the invention, what is claimed as new is:

1. The combination with a culvert or the like, of a lining freely received in the culvert and removable for cleaning the culvert of sediment deposited in the lining.
2. The combination with a culvert or the like, of a lining for the culvert composed of a plurality of mating units separately re-

movable for cleaning the culvert of sediment deposited in the lining.

3. In a culvert, the combination of a conduit, and a lining arranged within the conduit and composed of a plurality of mating units slidably fitting in the conduit and separately removable therefrom for cleaning the culvert of sediment deposited in the lining.

4. A culvert lining including a plurality of lining units freely insertable in a culvert to mate therein, forming a removable lining for the culvert.

5. A culvert lining including a plurality of longitudinally tapered lining units adapted to mate within a culvert forming a lining therefor.

6. A culvert lining including a plurality of lining units adapted to mate within a culvert forming a lining therefor, and means upon each of said units whereby the units may be separately withdrawn.

In testimony whereof I affix my signature.

ADELBERT AUSTIN. [L.S.]
